UNITED STATES PATENT OFFICE.

LESLIE A. BALDWIN, OF ST. LOUIS, MISSOURI, ASSIGNOR TO JOHNS-MANVILLE, INCORPORATED, OF NEW YORK, N. Y., A CORPORATION OF NEW YORK.

TANK COVER.

Application filed November 16, 1923. Serial No. 675,146.

This invention relates to tank covers comprising insulating materials and suitable for the roofs of out-of-door storage tanks for volatile liquids or low-pressure gases, or both, such as petroleum and refinery-products tanks.

Liquids of the kind referred to when stored in metallic tanks of usual types are subject to evaporation losses of serious volume selectively affecting the most valuable constituents of materials stored, especially during such times as the tanks are subjected to wide daily ranges of temperature, to heavy winds, or to excessive mean temperatures for considerable periods. The losses result from induced evaporation due to permitted changes in the surface temperature of the liquid and the temperature of the vapors in the space above the stored liquid, and to convection and escape of the vapors; the freed vapors cause undue fire risks and odor nuisances.

The diurnal fluctuation of temperature in the vapor spaces of tanks of the kind referred to provided with the usual covers on sunny days has been found to be of the order of 20° to 60° Fahrenheit, with corresponding fluctuation of temperature of the surface of the liquid (petroleum) of the order of 10° to 20° F., whereas the liquid at six inches to a foot beneath the surface remains at a temperature fairly constant, having a diurnal fluctuation of the order of 1° to 3° F. only. A consequence of the rising and falling surface and vapor space temperatures is of course expansion and contraction of the collected vapors, with escape of the vapors through the necessary vent-pipes and the crevices of the cover during expansion, and the intrusion of unsaturated air, capable of taking up more vapor, during contraction. This phenomenon is commonly referred to as "breathing" in the oil industry. Typical cases of these losses have been measured and computed by competent authority to reach 1500 barrels annually, in the case of a 55,000 barrel tank holding mid-continent crude, with corresponding losses amounting annually to 3,500 barrels in the case of 58° Baumé motor fuel, with some recession from these values when tank-covers of certain types of metal or wood and metal

construction, newly installed, are employed, the best practice then resulting in annual losses from average mid-continent crude of 55 about 400 barrels and of about 750 barrels for motor-fuel. Losses as low as these minima are seldom attained in actual practice, the expansion of walls and cover and the filling and emptying stresses on and motions of the tank walls resulting inevitably in crevices into and from which the wind-draft of air and vapor is substantial and costly. The storage losses in practice, especially of the gasoline fraction, may be assumed to average from three to four per centum.

An object of this invention is to provide for minimizing or preventing losses of stored liquids by evaporation or the expansion and escape of gases or vapors which may accumulate in the vapor space over the surface of such liquids, and for this purpose the invention provides a genus of heat reflecting and heat insulating gas-tight covers adapted for use with liquid storage tanks to cause the internal temperature of the contents of the tank to be maintained relatively constant and to prevent escape of vapors.

For example, the invention is exemplified by and will be described as applied to gas-tight heat-insulating roof and cover constructions adapted to enclose the tops of the storage tanks or chambers to be protected, to extend over the connections between the roof and the side wall of the storage tank, and to be joined to the side walls of the tank by a gas-tight expansible joint, and having features causing all joints and connections to be gas-tight and weather proof, enabling the heat insulation to be made impervious to gases and liquids, and permitting the outer surface, if desired, to reflect radiant heat, while preventing the substantial transmission of heat or passage of gases through the cover. The new cover is applicable to existing tank roof constructions.

In the instances of embodiments of the invention adapted for use with oil storage tanks illustrated in the accompanying drawings:

Fig. 1 is a vertical section representing a typical application of the invention to an oil storage tank having a wooden roof;

Fig. 2 is a similar vertical section representing a modification applied to an oil tank having a sheet or plate metal roof; and

Fig. 3 is a detail vertical section at one of the joints between the adjacent sheets of insulation according to the construction of Fig. 2.

In the drawings, Fig. 1 shows at 1 the side wall of an oil-tank of the usual cylindrical riveted-sheet metal type upon which the ordinary wooden roof 2 is supported by wood rafters or steel beams 3, in the common way. Attached to, and projecting over the edge of said roof are fastened by means of broad-headed nails 4 sheets 6 of suitable material, for example, compressed fibre board, metal, wood, or asbestos wood, having their outer edges bent downwardly into a curved portion 7. These sheets merely rest upon or extend just above the rim-stiffening metallic cornice 1^a of tank wall 1, and here provide the necessary sliding or free joint between roof and walls. The sheets 7 also support the overhanging flexible eaves sealing extension of the roof cover and prevent its becoming abraded or too sharply flexed at the edge of the roof. Joints at this place have heretofore provided a large leakage space, whatever type of cover may have been employed for the remainder of the wooden deck 2.

According to the present invention, a cover of gas-tight and weather-proof materials having a flexible and slack eaves-section to serve as an expansion joint is built in place about the top of the tank and on the deck 2. Preferred materials for this cover are laminated fabrics whose principal thickness is comprised of a non-conducting felt or mat of suitable fibrous texture, such as one or more sheets of a felt or bat of the well-known heat insulation materials, for example felted cattle-hair, asbestos, wood-fibre, vegetable fibre, mineral wool, cork, wool, cotton, diatomaceous earth, marsh grass or other or mixed coarse fibres, not herein claimed as new. The recommended material is a well-known fabric made up of a felted mat of cattle-hair with or without admixtures, enclosed between strong paper covers. For the purposes of the present invention, one of these covers is an asphalt saturated paper and the other cover is impregnated with sodium silicate in aqueous solution, or with any other satisfactory flexible gas-resisting impregnant, to fill interstices and aid in rendering the aggregate-laminated fabric impervious to gases. At the eaves this felted layer or layers is exteriorly protected and rendered impervious to gases and water by one or more layers of impervious canvas-asphalt, asbestos-asphalt, or other flexible sheet 9, preferably comprising a light canvas, cloth of asbestos fibres, a flexible fabric or an asbestos or other felt impregnated

with melted hard asphalt, fastened to the outside layer of insulating fabric or felt by suitable fusible cement, preferably consisting of the same asphalt as the impregnant. This layer may in turn be protected by a layer 29 comprising an asphaltic binder and mineral ingredients, such as asbestos and any suitable filler, for example, sand, calcined or uncalcined powdered stone, lime, ground calcareous matter or the like; but in the preferred construction, the greater part of the exposed surface of the roof, for example, the roof slope above line A, is finished by one or more layers of impervious water-laid asbestos-asphalt sheets 32, (or other asphalted sheets, such as rag-felt sheets) followed by a layer of weather-resisting white material 37, conveniently applied by attaching by suitable fusible cement, preferably asphalt to the upper surfaces in overlapping relation, sheets of water-laid asbestos felt impregnated with asphalt on their under sides only.

In order to construct this type of cover, the recommended procedure, referring to Fig. 1, is first to apply about the top of the wall 1 of the tank in a line substantially horizontal, a layer 11 of suitable cementitious adhesive, such as melted asphalt, into and by which the top edge only of a strip of the impervious canvas asphalt, asbestos-asphalt or other flexible fabric 9 is firmly embedded, any vertical seams being lapped and cemented. The strip 9 now hangs down from its horizontal upper edge and is washed over with a coating of melted asphalt 8, upon which is applied a layer 12 of the insulation fabric, which is in turn brushed with asphalt, and a wider strip for a layer 13 of the insulation felt applied.

The belt of laminated material thus built about the cylindrical wall 1 is now reinforced to prevent breakage of its gas-tight contact with the wall 1 by motions of the tank, wind or internal pressure. A preferred way of doing this is to encircle the whole tank and the applied fabric with a suitable compression binding, such as a metallic strip, or, as shown, two or more runs of strong wire cable 19, 19, which may be set up with any suitable clamp grips or turn-buckles, not shown, or welded or spliced under tension, and which serve to hold the applied fabrics firmly in place. Further to protect the fabric, a sealing strip of light canvas, light asbestos felt or light felted paper 20, impregnated with sodium silicate, may be cemented to the tank wall 1 and over the upper edge of the felt layer 19 with any suitable cement, such as silicate of soda. This keeps gases or oil out of the edges 14 of the cover material.

The eaves-plates 7 having been applied, the free lower edges of strips 9, 12 and 13 are now brought up over the edge, and sever-

ally fastened. The wider strip 13, which is preferably tapered in thickness to its edge 16, may be fastened to the wood deck with flat barbed nails 21 driven through flat metal caps 22. The edge 17 of the sheet 12 is similarly fastened, and forms a seat for the abutting edge of the next strip 18 of the felt material. The entire roof may be covered with two or more layers of the felt insulation material laid with broken joints, but in the usual case two layers at the eaves and one on the roof slope are sufficient. The insulation sheets 13, 18 etc. may be laid in an asphaltic cement if desired, but in the usual case this is not necessary, the outer layers of the roof providing a sufficiently impervious structure.

The outer layer 9 at the eaves is laid, preferably over the layer of insulating felt material 12 and over the joint at edge 17, in a liberal coat 31 of hot asphaltic cement and nailed at 21^a.

The roof slope to the break of the eaves at A is now covered with overlapped sheets of the water-laid asphalt impregnated asbestos felts, rag felts or other roofing sheets 32, laid in hot asphalt and preferably nailed frequently to the substructure through caps 22; over this, in layers 31 of melted asphalt or asphaltic cement, a further weather-proofing and heat insulating layer 37 of sheets or strips of asbestos felt, rag felt or other felted roofing sheets, preferably already impregnated on its under face only with the asphaltic impregnant, and preferably white on its exposed surface, is now laid to the line A, joints in this being overlapped, as at 38. The cover is completed by applying a relatively thick layer 29 of the plastic asphaltic cement, from the line A to the down-hang of the eaves, from which rain water drips clear of the tank from the curved portion C, which flexes slightly to accommodate the motions of the tank shell relative to its roof and cover.

Referring now to Fig. 2, tanks having metal roof-decks 43 may be protected according to the same principles, with variation of the mode of attachment of the protective cover. An impervious strip or sheet 47, preferably of the canvas-asphalt, the asbestos-asphalt or other flexible fabric material, is first fastened to the cylindrical wall 41 near the top by a belt of asphaltic cement 44 applied to the wall, and is then coated with a layer 46 of cement or melted asphalt, into which the lower edge of a relatively stiff sheet 49 of impregnated asbestos felts, asphalt saturated rag felts or a combination of both or other suitable material is embedded. Sheet 49 may be a flashing felt of well-known construction; any flexible protective material capable of supporting the remainder of the eaves section of the protective roof against the cutting and rub-

bing stresses of the tank edges is suitable; a stiff felt is preferred because it can be strongly attached to the metal roof by a layer 48 of hot asphalt mopped on. The strip or sheets 49 may thus be attached, to 70 overhang, as the first operation of assembly, the lower edge being adjusted and fastened after the impregnated strip 47 is attached at 44. A strip 51 of the above described insulating felt sheet, preferably having an 75 edge tapered at 54, is now applied in a layer of hot asphalt at 52^a and at 52, this strip being of sufficient width to have its edge reach the illustrated position when bent over the sheets 49. Upon the strip 51, in a layer 80 of hot asphalt, a second strip of insulation felt 53 is now laid; and a binding wire 50 may now be wrapped about the tank to hold the lower edges of the insulation felt and form a guide, about which the impervious-fabric strip 47 is now turned up and over into a layer of hot asphalt 61. The layer 61 may extend over the down-hung part of sheet 53, but preferably the cement layer 46 on the now inner face of strip 47 is supplemented by a cementitious coat on this down-hung part of the sheet 53, the hot asphalt layer beginning under the circumferential line B.

The strip 47 is wide enough to overlap the 95 inward edge of the strip 43, and is sharply bent downwardly and then inwardly at 62 for attachment directly to the deck 43 by a layer of asphalt 55, and thus provides a seat for the abutting edge of the next strip 57 100 of insulation felt.

At each radial and circumferential joint of the strips of insulation felt 57, it is preferred to attach the upper edge of the outer strip in this manner, as shown in Fig. 3, in 105 which a narrow strip 65 of the canvas asphalt, asbestos asphalt or other flexible fabric material is shown as applied to the top of an outer or lower strip, and bent downward at 59 and inward at 56, to form a seat for the lower or outer edge of a felt strip 57. All crevices in this construction are filled at 58 with the attaching asphalt or a cement.

From the circumferential line B the remainder of the cover is built up of asphalt 115 impregnated asbestos felts, rag felts or other roofing sheets or strips 66 laid in lapped relation in melted asphalt, and topped with sheets or strips of asbestos felt 67, 68 impregnated on one side only to provide a 120 white surface and overlapped as at 69.

The eaves structure is preferably firmly held in engagement with the tank by an encircling wire cable 60, which, together with the down-hang from the line B, may be covered with a suitable plastic water proof cement 70, preferably the same material above described or preferred for the layer 29, Fig. 1.

To accommodate varying conditions of 130

tank structure it will be understood that the constructions exemplified by those shown in Fig. 1 or Fig. 2 may be interchangeably resorted to in whole or in part, depending upon the structure of the tank, to construct covers for wood or steel deck tanks of different kinds.

It will be understood that the elements of the improved cover are sufficiently ductile and extensible to enable them to be applied to conform to the large circumferential circles of the tank top without difficulty, but for small tanks, the materials employed may comprise sheets lapped frequently at radial joints to permit edges of the sheets to lie on chords of the circles defined by their assembled positions.

In each instance of the invention, the necessary hatches and vent pipes may be sealed around by the cover materials, or otherwise, in order to assure a vapor-tight heat-resisting construction. At least one vent pipe is necessarily left open to prevent any considerable internal pressure from building up. But with efficient heat and wind insulation and sealing, as herein provided, the large breathing or diurnal expansion losses and the wind-drift losses are so nearly prevented by prevention of rapid variation of the internal temperature and efficient sealing that the output of vapor through the vent pipe is reduced to a mere seasonal loss, during rises of the mean temperature, and such incidents as the loss of vapor during filling of the tank. These losses are not serious in volume or frequency.

It will be observed that this invention provides a sealing and insulation cover capable of being applied to all types of existing tanks and serving to cause the interior temperature to be maintained nearly constant under diurnal temperature changes, and capable of resisting the effects of relative movement of the parts of the tank which

have heretofore resulted in leakage and loss of vapors.

I claim:

1. The combination of a tank having a roof and a wall with a flexible cover adapted to seal spaces between the tank roof and its wall comprising a heat insulation layer and laminae of paper resistant to the penetration of hydrocarbon vapors, and having a lamina of a water-proof heat-resistant fabric interpenetrated by a continuous asphaltic inclusion.

2. A tank of the kind having a wall and a roof, and having a flexible cover adapted to seal spaces between the tank roof and its wall comprising a heat insulation layer and laminae of paper resistant to the penetration of hydrocarbon vapors, and having a lamina of a water-proof heat-resistant fabric interpenetrated by a continuous asphaltic inclusion, and a lamina having a white exterior face.

3. A roof construction for tanks comprising a flexible cover adapted to seal spaces between the roof of a roofed tank and its wall comprising a heat insulation layer and laminae of paper resistant to the penetration of hydrocarbon vapors, and having a lamina of a water-proof heat-resistant fabric interpenetrated by a continuous asphaltic inclusion, and a lamina having a weather-resistant white exterior face of asbestos fibre.

4. A flexible cover adapted to seal spaces between a tank roof and its wall comprising a heat insulation layer and laminae of paper impregnated with a flexible saturant adapted to render the paper resistant to the penetration of hydrocarbon vapors, and having a lamina of a water-proof heat-resistant fabric interpenetrated by a continuous asphaltic inclusion.

Signed by me at St. Louis Missouri this First day of November, 1923.

LESLIE A. BALDWIN.
